UNITED STATES PATENT OFFICE.

FRANCIS LEE STUART, OF GREENWICH, CONNECTICUT.

CONVEYER SYSTEM.

1,339,486.

Specification of Letters Patent. Patented May 11, 1920.

Application filed October 12, 1917. Serial No. 196,187.

To all whom it may concern:

Be it known that I, FRANCIS LEE STUART, a citizen of the United States, residing at Greenwich, in the county of Fairfield and State of Connecticut, have invented certain new and useful Improvements in Conveyer Systems, of which the following is a specification.

My invention relates to means for conveying material from one place to another by means of endless belts and the like, and it provides improved means whereby the material is quickly and efficiently handled.

More specifically, my invention relates to conveyer systems having a plurality of traveling conveyers such as a succession of endless belts or the like, arranged to transfer material from suitable receptacles, such as storage bins, hoppers and the like, to other receptacles at a distance, and it has for one of its objects the provision of an improved arrangement whereby the belts are started and stopped and generally controlled in a safe, reliable and efficient manner.

In certain of its aspects, my invention is particularly applicable to a conveyer system such as shown, described and claimed in my pending application, Serial No. 55,620, filed Oct. 13, 1915, as well as the arrangements disclosed in my Letters Patent No. 1,192,016, granted July 25, 1916, No. 1,204,203, granted November 7, 1916, No. 1,207,237, granted December 5, 1916, No. 1,230,236, granted June 19, 1917, and No. 1,231,449, granted June 26, 1917, and those skilled in the art will readily understand the adaptation of the principle of this invention to arrangements embodying the features of those former applications for patents.

The novel features which I believe to be characteristic of my invention will be definitely indicated in the claims appended hereto; the features of construction, mode of operation, and further objects of my invention will be readily understood from a consideration of the following description taken in connection with the accompanying drawings wherein I have shown an embodiment of my invention.

Referring to the drawings, Figure 1 shows a simplified diagram of a plan view of a conveyer system having a plurality of endless belts adapted to convey material from cars to vessels or the like located at a distance; Fig. 1^a shows diagrammatically

a certain arrangement of belts; Fig. 2 shows an elevation of the system shown in Fig. 1; Fig. 3 shows in simplified diagram a control for the driving motors of the system shown in Figs. 1 and 2; Fig. 4 shows in simplified diagram a control for the driving motors which embodies the features of Fig. 3 but has means combined with the arrangement of Fig. 3 for accomplishing further objects; Figs. 5 to 9, inclusive, are details of certain features of Fig. 4.

Referring to Figs. 1 and 2, the car 1, having coal or other material which it is desired shall be delivered to the ship 2, is adapted to be held in the pivoted cradle 3 which is elevated by any suitable means so that the coal or other material will spill from the car into the lowering bin 4. While a car is being emptied the lowering bin is held in the elevated position shown in dotted lines in Fig. 2 so that the material will pour out of the car with but a slight drop, thereby reducing breakage of the material. This lowering bin is adapted to be lowered and raised by the cable 5, the arrangement being such that after the material from the car 1 has been transferred to this lowering bin, it is lowered from the dotted to the full line position gradually so that the coal or other material in the bin will not be broken by reason of being suddenly dropped into the hopper 6. Associated with this hopper 6 is a feeder belt 7 driven by any suitable motor, such as an electric motor 8. The hopper is provided with delivery ends 9 and 10 through which the material is lowered to the main conveyer belts 11 and 11^a, respectively. The main conveyer belt 11 is of the endless type and is suitably arranged so that the effective portion of the belt may be lengthened or shortened as desired, as fully explained in my former application for patent Serial No. 55,620. This belt 11 is driven by any suitable motor, such as an electric motor 12, and it is adapted to deliver the material to the hopper 13, through which it is permitted to slide to the endless belt 14 which delivers it to the ship 2. This endless belt 14 is adapted to be driven by any suitable motor, such as the electric motor 15.

Associated with the main conveyer belt 11 at some suitable place between the receiving and delivery end of this belt is a storage bin 16. Material from the hopper 6 is delivered through the chute 10 to the belt 11^a.

which transfers the material to a suitable hopper (not shown) and from there it is delivered to the storage bin 16 by the endless belt 17. Associated with the chute 10 is a feeder belt (not shown), similar to the belt 7 associated with the main conveyer belt 11, and this belt like the feeder belt 7, is driven by a suitable motor such as the electric motor 18. The delivery belt 17 is likewise driven by any suitable motor such as the electric motor 19. The storage bin 16 is provided with two pivoted directing delivery chutes 20 and 21 which are ordinarily held up out of the way of the material on the belt 11 by means of the counter weights 22 and 23, respectively. The feeder belt 24, associated with the chute 21 is adapted to be driven by the electric motor 25 and the feeder belt 26 is adapted to be driven by the electric motor 27.

In Fig. 3 I have shown a control for the driving motors of Figs. 1 and 2 whereby I am able to obtain certain of the objects of my invention. This control is diagrammatic and is intended to serve merely as an illustration of means for carrying my invention into effect. The control for the belts 11^a, 17, and the feeder belt not shown, has been omitted for the sake of clearness, since those skilled in the art will readily understand the adaptation of the control embodied in the arrangement for driving the belts 7, 11, 14, 24 and 26 shown in Fig. 3, to the control of the belts for supplying the storage bin.

In general, it may be said that this control is adapted to accomplish the following results. These belts are of various lengths and have different inertia effects so that to provide against material being spilled when the belts are started and stopped, I have arranged the control for the motors driving these belts in such a manner that the delivery belt 14 will be started first and be brought up to an appreciable speed before the motor driving the main conveyer belt 11 is started. After this main conveyer belt 11 is started and brought up to an appreciable speed, the feeder belt 7 is started so as to deliver material to the system of belts. By having these belts start in this manner practically no material will be spilled, because each belt will be brought up to practically full operating speed before any material is delivered to it from the next preceding belt of the system. In order to provide against the material being spilled when the belts are stopped, I arrange the control in such a manner that the feeder belt 7 is stopped first, the main conveyer next and finally the delivery belt 14 stopped last. By this arrangement, no material can be spilled from one of the belts in the series to a belt which is stationary, since the delivery of the material to each belt is stopped before

the motion of the belt itself is arrested. If desired, the carrying surface of the belts 11 and 14 can be made of such size that material will not be delivered to these belts faster than they can satisfactorily carry off; that is, the belt 11 shall be wider than the feeder belt 7 and the belt 14 shall be wider than the belt 11, as shown in Fig. 1^a.

In order to provide for regulating the amount of material delivered by the conveying system, I provide for varying the speed of the feeder belt from the delivery end of the system, or for operating the belts a portion of the time. Since the amount that each belt can carry away from the preceding belt of the system is fairly accurately determinable, I arrange the control in such a manner that the delivery belt 14 will ordinarily be operated at the highest speed, the main conveyer belt 11 at a somewhat lower speed and the feeder belt 7 at the lowest speed of the belt system, thereby preserving a relation between the belts such that no belt of the system can deliver to the next succeeding a greater amount of material than the succeeding belts can satisfactorily carry off, assuming that the belts 11 and 14 have the same carrying surface. While my arrangement is such that the speeds of the motors driving the belts 7, 11, 14, and 24, can ordinarily be independently varied, they cannot be varied to such an extent that this effective relation between the various belts is destroyed. I also provide means whereby the amount of material delivered is controllable from any suitable place, such as the delivery end of the system, by simultaneously varying the speeds of all the belts of the system. The arrangement is such, however, that the belt speeds are varied proportionately so as to preserve the most effective relation between the speeds of the various belts.

In order to avoid wear on the feeder belt 7 and main belt 11 due to the material being dropped directly from the lowering bin 4 through the hopper 6 on to these belts, I provide for always retaining a certain amount of material in the hopper 6 to act as a cushion for receiving the next load from the lowering bin, the arrangement being such that when the material has been fully discharged from the lowering bin 4 to the hopper 6, the lowering bin is raised from its seat by means such as a spring 28, thereby operating a switching arrangement to stop the motor 8 driving the feeder belt 7. When the lowering bin is again seated by a predetermined weight in the bin, this switching mechanism is operated to automatically start up the motor 8 so as to feed material to the main conveyer belt. This starting and stopping of the feeder belt, dependent upon the material in the hopper and the lowering bin, is entirely automatic.

and independent of the control by the operator at the delivery end of the system. However, in order to save power and belt wear I have arranged the control for the 5 driving motors so that if desired, the main discharge belts are automatically stopped in sequence after the feeder belt has been stopped and after the main belt has discharged its material to the discharge belt 14 10 at the end of the system. When the lowering bin is again seated by a predetermined weight of material, the belts are again automatically started in the proper sequence, that is, belt 14 first, 11 second and the 15 feeder belt 7 last.

In order to insure that the material will be continuously delivered to the vessel or the like which is to be filled, I have provided the storage bin 16. The control for the 20 belts supplying the material to this bin is similar to the control for the belt supplying material to the ship 2 and will not be further described since the principle of operation is the same as that which will be described in 25 connection with the belt system 7, 11 and 14. Assuming that there is a suitable amount of material in the storage bin 16, and that the supply from the cars at the receiving end of the system has temporarily 30 ceased, and that it is desired that the delivery of the material to the ship shall continue I have provided an arrangement whereby after the feeder belt 7 has stopped and the material on the belt 11 has proceeded past the storage bin 16, either the chute 20 or 21 will be lowered so as to deliver material to the main conveyer 11, the arrangement being such that the proper sequence of starting and stopping for the 35 belts 24 or 26 and the belts 11 and 14 will be preserved in the same manner as that indicated above in connection with the belts 7, 11 and 14, that is, in stopping, either belt 24 or 26 depending upon the one being used, 40 will be stopped first, the belt 11 next and finally belt 14 last. Likewise in starting the belt 14 will be started first, the belt 11 second and the belt 24 or 26 last. When the 45 delivery of material to the hopper 6 has again been resumed, the chutes 21, 20 are automatically elevated from the main belt, the feeder belts 24, 26 are stopped and the feeder belt 7 automatically started.

Referring now to Fig. 3, the electric motor 15 driving the delivery belt 14 is 50 adapted to be started by means comprising the electromagnetic line switch or contactor 29, and the accelerating contactors 30 and 31, which are of the well known series type 55 adapted to hold open until the motor current at starting has dropped to a predetermined value, are closed in succession thereby short circuiting sections of the starting resistance. The contactor 30 in closing is 60 adapted to short circuit the starting resist-

ance 32 and also include the series operating coil of the contactor 31 in the motor circuit and the contactor 31 is adapted to close when the motor current has again dropped to the predetermined value and short circuit 70 the starting resistance 33. A variable rheostat 34 in circuit with the shunt field 35 of the motor 15 is provided for varying the speed of this motor independently of the speeds of the other driving motors of 75 the system. The motor 12 driving the main conveyer belt is likewise started by means of a control similar to the starting arrangement for the motor 15. For the sake of simplicity this automatic gradual starter 80 has not been shown, but is indicated at 36. The motor 8 driving the feeder belt 7 is likewise gradually started by means of a similar starter indicated at 37, and the motors 25, and 27 driving the feeder belts 24 85 and 26, respectively, are started by means of similar starting arrangements indicated at 38 and 39, respectively.

The speed of the driving motor 12 of the main belt 11 is independently varied by 90 means of the field rheostat 40 and the speed of the motor 8 is likewise varied by means of the field rheostat 41, the arrangement being similar to that described in connection with the driving motor 15 for the discharge 95 belt 14. The belts 14, 11 and 7 are started in the succession named by means of an electromagnetic switch 42 which controls the line contactor 29 for the motor 15, as well as the line contactor 43 for the motor 100 12 and the line contactor 44 of the motor 8. The switch 42 has a dash-pot 45 which provides a definite time interval between the starting of the different motors. A dash-pot 46 is also provided to give a definite 105 time interval for stopping the motors in succession. The operation of this switch 42 is such that the motor 8 driving the feeder belt 7 will be first stopped and then after a definite interval the motor 12 driving the 110 main belt 11 will be stopped, and finally after a definite time interval the motor 15 driving the delivery belt 14 will be stopped.

In order to provide for varying the speeds of the motors 8, 12 and 14 simultaneously, 115 at the same time preserving the relation between the speeds of the various motors as determined by the setting of the field rheostats 41, 40 and 34, respectively, I have provided a rheostat 47 having an independent 120 section of resistance in each of the motor field circuits. This field rheostat 47 has a common operating member whereby after the switch members of this rheostat are properly adjusted, a movement of the rheostat will vary the speeds of the driving motors 8, 12 and 15 simultaneously in the 125 proper proportion.

In order to provide for automatically 130 stopping the belts when material is not be-

ing delivered to the lowering bin 4, I have provided switch mechanism having contact members 49, 50 and 51 which are raised from their respective contacts when the 5 lowering bin 4 is raised from its seat by the spring 28 when the material has been delivered from the lowering bin to the hopper 6. An electromagnetic switch mechanism 52 similar to the electromagnetic 10 switch mechanism 42 is controlled by the contact member 50, the arrangement being such that when the material has been delivered from the lowering bin to the hopper and the lowering bin has raised from its 15 seat as before described, the coil of electromagnetic switch 52 will be deenergized and its switch member will drop, deenergizing the motors 8, 12 and 15 in succession, definite time intervals between the deenergization of the motors being provided by 20 means of the dash-pot 53 and the spacing of the switch contacts. When the lowering bin is again filled and its weight is such that the contact member 50 is deenergized so as to make engagement with its 25 contacts, the coil of electromagnetic switch 52 is again energized and the motors are automatically started in the succession 15, 12 and 8, a definite time interval between 30 the starting of these motors being provided by means of the dash-pot 54.

The motor 55 is provided for raising and lowering the directing chute 20 which has been provided for delivering material from 35 the storage reservoir 16 to the auxiliary feeder belt 26 and thus to the main conveyer belt 11. The motor 56 is provided for raising and lowering the directing chute 21 associated with the auxiliary feeder belt 24. 40 A movable switch member 57 is operated by the motor 55 and the arrangement is such that when the motor 55 has lowered the chute 20 so as to properly deliver material from the feeder 26, the motor 27 is automatically energized to start the belt 26, at 45 the same time the solenoid brake 58 is energized to hold the motor 55 in the position at which the directing chute 20 is in proper position to deliver material from the belt 26. A similar controller 59 is provided 50 with the motor 56 and is adapted to accomplish the same purpose in connection with this motor that the controller 57 accomplishes in connection with the motor 55. 55 The arrangement of switches and the circuit connections are such that when the manually operated switch 60 is thrown so as to make engagement with the lower contacts, and the lowering bin 4 has been raised 60 from its seat in the manner heretofore explained, the motor 8 driving the feeder belt 7 will be deenergized and either the motor 55 or 56, depending upon the position of the controller 61, will be energized to lower 65 its directing chute to a proper position over its corresponding feeder. After either one of these directing delivery chutes has been lowered to such a position, either the motor 25 or 27, depending upon the delivery chute selected, will be automatically energized to 70 operate its corresponding belt a predetermined interval after the stopping of the motor 8 driving the feeder 7. When material has been supplied to the lowering bin 4 sufficient to lower the contact members 49, 50 and 51 into engagement with their respective contacts, the motor 8 driving the feeder 7 is automatically energized and after an interval determined by the setting of the dash-pot 62 of the electromagnetic switch 80 63, the motors 55 and 56 are deenergized. Assume that the motor 55 has been the one selected for operation, when it is deenergized, the electromagnetic line switch 64 is opened and the contact member 65 of this 85 switch is closed, connecting the motor 56 in a dynamic braking circuit so as to permit the delivery chute 21 to be raised by the counter weight 23 at a safe speed. The line switch 66 for the motor 55 has a contact 90 member 67 which likewise includes the motor 55 in a dynamic braking circuit when it is deenergized.

As thus constructed and arranged, the operation of my invention as shown in Figs. 1, 95 2 and 3 is as follows:

Assuming that the parts are in the various positions shown in the figures, except that the contact members 49, 50 and 51 are in engagement with their respective contacts, and that it is desired to deliver material from the lowering bin 4 to the hopper 6 and from there to the ship 2 at the end of the conveyer system. The controller 61 will first be turned to the position *a*, and the manually operated switch 68 turned to the left so as to make engagement with its contacts. Upon closing the pilot switch 69, the coil of electromagnetic switch 42 will be energized and the contact member of this 100 switch will first make engagement with the contact 70, thereby energizing the electromagnetic line switch 29 for the motor 15 and connecting this motor to the source of supply. The motor 15 will be gradually 105 started through the operation of the series contactors 30 and 31, in a well known manner, and this motor 15 will run at a speed determined by the setting of the field rheostats 34 and 47. After a time interval, determined by the setting of the dash-pot 45, the switch member 42 will make engagement with the contact 71, thereby energizing the electromagnetic line switch 43 for the motor 12, through a circuit from the source of 110 supply, contact member of electromagnetic switch 42, contact 71, through the middle blade of the manually operated switch 68 through the coil of the line contactor 43 to ground. The motor 12 will thereby be 115 120 125 130

started gradually by the starter 36 and its speed will be determined by the setting of the field rheostats 40 and 47. After a pre-determined interval, engagement will be 5 made with the contact 72, thereby energizing the electromagnetic line switch 44 for motor 8, through a circuit from the source of supply, switch member of electromagnetic switch 42, contact 72, right hand blade 10 of manual switch 68, contact member 51, segments 73 and 74 of controller 61 to ground. (It is understood of course that the switch members 49, 50 and 51 are closed since it has been assumed that there is a load 15 of material in the lowering bin 4). The motor 8 is thus energized from the source of supply through a circuit including the contact member of electromagnetic switch 44, upper contact blade of switch 60 through 20 the starter 37. If the switch 69 is closed before the switches 49, 50 and 51 are closed, it will readily be understood that motors 15 and 12 will start in succession but motor 8 will not start until the contact 51 is closed. 25 In case the speeds of the belts are not such that they will have the proper relation for the most efficient operation, the speeds of motors 15, 12 and 8 may be independently varied by means of the field rheostats 34, 40 30 and 41, respectively. After this proper relation of the speeds of the various belts is determined, in case it is desired to either increase or decrease the output of the conveying system as a whole, this can be done by 35 moving the field rheostat 47, thereby simultaneously affecting speeds of the motors and at the same time preserving the proper relation of the different belt speeds. The closing of the pilot switch 69 likewise 40 energizes the coil of electromagnetic switch 52, the circuit being from the source of supply through the contact member 50, coil of the switch to ground. This switch will then gradually raise its contact member, but this 45 will produce no effect since the contacts associated with this switch are short circuited by means of the manual switch 68. Assuming that the belts have operated until the material has been delivered from the lowering 50 bin 4 so that this bin is raised from its seat in accordance with its bias, the contact members 49, 50 and 51 will break engagement with their respective contacts, and the circuit for the coil of electromagnetic line 55 switch 44 is opened at the contact member 51. The motor will thereby be deenergized and no further material will be delivered to the main conveyer belt 11. The main conveyer belt and the delivery belt will however 60 continue to run. As soon as the lowering bin 4 receives another supply of material so as to close the contacts 49, 50 and 51, the motor 8 is again automatically started. If it is desired to stop the delivery 65 of material to the belt 11, the controller 61 will be turned to the off position, thereby deenergizing the coil of line contactor 44 of motor 8, causing this motor to be deenergized and the belt 7 to be stopped. The belts 11 and 14 will nevertheless continue to run. 70 Assuming that the controller 61 is in position *a*, if it is desired that the main conveyer and delivery belts be also stopped, as well as the feeder belt when the contacts 49, 50 and 51 are raised from engagement 75 with their respective contacts, the manual switch 68 will be thrown to the position shown in the drawing. If now the contact members 49, 50 and 51 are raised from engagement with their respective contacts 80 due to an elevation of the lowering bin 4 in accordance with its bias, the coil of the electromagnetic switch 52 will be deenergized at the switch member 50 and the switch member will drop gradually under 85 the restraining influence of the dash-pot 53. The switch member 51 will, as before, deenergize the coil of the line contactor 44 for the motor 8 and this motor will thereby be first promptly deenergized. The electromagnetic switch 52 in dropping will in turn deenergize the motor 12 at the contacts 75 and the motor 15 at the contacts 76, the motors 8, 12 and 15 being thereby deenergized in the desired succession. The switch 90 members 49, 50 and 51 will be again closed on their contacts when another load of material has been delivered to the lowering bin, as before explained. This will cause the reenergization of the coil of switch 52 95 and this switch will be gradually raised under the influence of the dash-pot 54, the line contactor 29 for the motor 15 being first energized by completing the circuit at contacts 76, the line contactor 43 for the motor 12 energized at the contact 75, and finally the line contactor 44 for the motor 8 will be energized at the contacts 77. It has here been assumed that the pilot switch 100 69 has been retained closed and the electromagnetic switch 42 has retained its switch member in the up position. It can thus be seen that the motors driving the various 105 belts are automatically started and stopped in the desired sequence. 110

In case the supply of material to the lowering bin is about to cease temporarily and it is desired that the supply of material to the ship or other carrier being loaded by the conveyer system shall continue; by throwing the manual switch 60 so that it makes engagement with its lower contacts, and by turning the controller 61 to the position *b*, the motor 8 will continue to operate as long as there is material in the lowering bin, but arrangements have now been made whereby the material in the storage bin 16 can supply material to the conveyer system at the proper time. The coil of the supplementary line contactor 78 for the 115 120 125 130

motor 8 is energized from the source of supply through the switch member 49, and the motor 8 will be energized from the source of supply through a circuit including the 5 switch member of contactor 78, and the upper blade of switch 60. The coil of the electromagnetic switch 63 is also energized from the source of supply through the switch member 49, and this switch will 10 break engagement with its corresponding contact. As soon as the switch members 49, 50 and 51 are raised from their respective contacts the coils of electromagnetic switches 78 and 63 will be deenergized at the switch 15 member 49. The resulting opening of line contactor 78 will deenergize the motor 8 and the switch 63 will drop under the influence of the dash-pot 79. This dash-pot has been provided to give a time interval so 20 that the material on the belt 11 will have been moved past the storage bin before any material is supplied to this belt from that bin. After an interval has elapsed, the switch member will make engagement with 25 its corresponding contact and thereby energize the line contactor 64 of the motor 56 through a circuit from the source of supply, switch member of electromagnetic switch 63, lower blade of manual switch 60 and segments 30 80 and 81 of the controller 61 and segments 83, 82 of controller 59 operated by the motor 56. The motor 56 will thereby be energized to lower the delivery chute 21 and when the chute has been fully lowered 35 the line contactor 64 for motor 56 will be deenergized at the segments 82 and 83, thereby deenergizing this motor. The solenoid brake 84 is simultaneously energized with the deenergization of the line contactor 64 40 and this brake will bring the motor to rest gradually and hold the chute 21 in its lower position against the tendency of the counter weight 23 to raise the chute. It will also be noticed that the deenergization of the 45 line contactor 64 has caused the switch member 65 to include the motor 56 in a dynamic braking circuit. The line contactor 85 for the motor 25 is energized to close simultaneously with the deenergization of the line 50 contactor 64 and the motor 25 will be energized from the source of supply and gradually started by means of the starter 38. The auxiliary feeder belt 24 is thus started at the proper interval after the stopping of 55 the feeder belt 7. If it is desired that the auxiliary feeder belt 26 shall be used instead of the belt 24, the controller 61 will be turned to the position *c* and the operation of the motors 55 and 27 will in this case be 60 similar to that above described in connection with the operation of the motors 56 and 25.

Assume that the motor 25 is operating as above described and it is desired that the 65 supply of material to the belt 11 shall cease

for an interval, the controller 61 will be turned to the "off" position, thereby deenergizing the motor 25 and the solenoid brake 84. The delivery chute 21 will be gradually elevated by counter weight 23, 70 and the motor 56 now being included in a dynamic braking circuit will operate as a generator so as to cause the chute to be elevated gradually. The belts 11 and 14 will however continue to run. When it is desired that the supply of materials from the storage shall be resumed, the controller 61 will be turned to either the position *b* or *c*, 75 depending upon the belt 24 or 26 which it is desired shall feed material to the main 80 belt 11.

Assume that the auxiliary feeder belt 24 is being operated as above explained and that the supply of material to the lowering bin 4 is resumed. When the switch members 85 49, 50 and 51 make engagement with their respective contacts, the line contactor 78 for motor 8 will be energized to close and connect the motor 8 to the source of supply. The coil of electro-magnetic switch 63 will 90 also be energized and this switch will gradually raise its switch member out of engagement with its corresponding contact. When this happens the solenoid brake 48 and the line contactor 85 for the motor 25 are deenergized and the belt 24 automatically stopped. The delivery chute 21 will be automatically gradually elevated in the manner heretofore explained. The belt 24 will be stopped and the delivery chute 21 will be 100 elevated before the material being supplied to the main conveyer belt 11 by the feeder belt 7 has reached the delivery chute 21, thereby avoiding delivery of material to the belt 11 at a time when it is already fully 105 loaded. In order to stop the entire equipment the switches 69, 68, 61 and 60 will be operated in a manner obvious to those skilled in the art.

In Fig. 4 I have shown in simplified diagram an arrangement for controlling the driving motors which embodies all of the features of Fig. 3 but has means combined with the arrangement shown in Fig. 3 whereby further objects may be obtained. 110 In general, it may be said that with this arrangement shown in Fig. 4 I am able to control the conveyer belts in such a way that the feeder belts may be operated either singly or in various combinations so as to 115 deliver material to the belt 11, which, it will be understood is a delivery belt for the feeder belts, in such a manner that predetermined amounts of material may be taken from the various receptacles and delivered 120 by the system in a predetermined manner. 125

With this arrangement, I am able to not only carry out the objects sought in connection with the arrangement shown in Figs. 1, 2 and 3, but a great variety of further, 130

useful objects are obtained. Thus by filling the receptacles 6', 86 and 87 with suitable materials, I am able to charge blast furnaces, coke ovens or the like, mix medicines, 5 clays, ore, coal or the like, assemble parts of a machine, fill receptacles with various materials and articles, deliver glassware, projectiles, packages, or the like to be loaded in ships, box cars or other receptacles, as well 10 as numerous other uses which will be obvious to those skilled in the art from an understanding of the invention. It will be understood that the receptacles 86 and 87 are not necessarily a part of the storage 16 15 shown in Figs. 1 and 2 but that these receptacles may be entirely independent, as shown in Fig. 4; nor is the hopper 6' necessarily the same receptacle as that designated by the numeral 6 in Fig. 3, although, of course, it may be. These receptacles may be 20 filled in any suitable manner.

With this arrangement, I am able to deliver from the final delivery belt 14, composite material made up of layers of predetermined amounts taken from each of the receptacles 6', 86 and 87, or a predetermined amount from one receptacle followed by predetermined amounts from the other receptacles in succession, the material from 25 each receptacle taking up a section of the belt. Means are provided whereby any desired predetermined order of delivery of material from the receptacles to the belt 11 may be had; that is, the feeder belts may be 30 operated continuously, intermittently, or successively; or the entire system operated continuously or for predetermined intervals so as to deliver material from the belt 14 in any desired manner, the arrangement being 35 such, however, that the feeder belts cannot feed more material to the belt 11 than this belt and belt 14 can properly carry off. Means are also provided whereby the control of the system is responsive to the material in the receptacles; that is, the arrangement is such that if the material in any one of the receptacles becomes less than a predetermined amount, the system will be 40 automatically stopped, the belts being stopped in the proper sequence as set forth 45 in the description of Fig. 3; and in case the supply of material in the receptacle is replenished, the belts are automatically started in the proper sequence. Means are also provided 50 for regulating the amount of material delivered from the receptacle, the arrangement being such that the speeds of the feeder belts are automatically controlled so as to maintain a substantially uniform delivery 55 of material from the various receptacles and in case any abnormal conditions occur such as a failure of the feeder belts to deliver material or to deliver more than a safe maximum, the system will be automatically shut 60 down.

In Fig. 4 the reference numerals similar to those found in Fig. 3 designate the same pieces of apparatus and these pieces of apparatus are intended to operate in the same manner as in Fig. 3. 70

A particular description of such apparatus will not be given here because it is thought that an understanding of Fig. 3 will be sufficient.

The controller 155 provides an arrangement whereby the speeds of the feeder belts may be individually controlled and the speeds of the delivery belts 11 and 14 simultaneously controlled so as to be increased or decreased in a predetermined ratio to the increase or decrease of the speeds of the feeder belts, thus providing for satisfactorily carrying off the material on the belts 11 and 14 when the amount of material delivered to these belts is varied and automatically limiting the amount of material to the capacity of the delivery belt. The controller comprises a contact lever fulcrumed at its middle point 88 and having two arms of equal length, the one arm having a contact 89 for 90 energizing the line contactor 90 to close the circuit of the motor 8 driving the feeder belt 7 and another contact 91 for varying the resistance in the field of the motor 8 so as to vary the speed of this motor. The 95 other arm has a contact 92 for energizing the line contactor 64 of the motor 56 so as to lower the directing chute 21 and energize the motor 25 driving the feeder belt 24 when the chute is fully lowered. A contact 93 is 100 also provided for varying the resistance in the field of motor 25. The controller has also a contact lever fulcrumed at 94, the end of one arm of which forms the hinged fulcrum 88 for the contact lever previously 105 mentioned. This arm is one-half the length of the other arm to which the contact 95 for energizing the line contactor 66 for the motor 55 and the contact 96 for varying the resistance in the field of the motor 27 are attached. The contacts 97 and 98 for varying resistances in the fields of the motors 12 and 15, respectively, are attached to the remaining arm of the controller which is hinged at 94. The controller 155 provides 110 an arrangement whereby any one, all or any desired combination of the motors 8, 25 and 27 driving the feeder belts may be operated and the speeds of these motors independently varied. A movement of any one of 115 the arms for varying the speed of its corresponding motor will produce one-third of the movement in the contacts 97 and 98 for varying the speeds of the motors 12 and 15, respectively. Thus, a movement of one of 120 the arms one unit of distance will produce a movement of one-third the unit in the contacts 97 and 98; with the first arm left in that position, a movement of another arm a unit of distance will produce another move- 125 130

- ment of one-third the unit in the contacts 97 and 98; and the movement of the last arm a unit of distance will produce a corresponding movement of one-third the unit.
- 5 In that manner, a movement of all the arms a unit of distance will produce a movement of the contacts 97 and 98 a unit of distance, or a movement of any one of the arms three units of distance will produce a movement 10 of the contacts 97 and 98 a unit of distance. This provides for varying the speeds of the feeder belts so as to deliver any predetermined amount of material and at the same time varies the speed of the belts 11 and 14 15 so as to properly carry off the material delivered. The value of the resistance in the motor fields will be predetermined so as to carry this object into effect. Any preferred form of controller may be employed.
- 20 The regulator 99 is provided for maintaining the delivery of a predetermined amount of material from the receptacle 6'. Each of the receptacles 86 and 87 is provided with a similar regulator, although for 25 the sake of clearness in the drawing certain of the parts of the regulators for these receptacles are not shown. For an understanding of this device, attention is directed to Figs. 5 and 6 as these figures show 30 the device more in detail. The switch members 100, 101 and 102, associated with the feeder belts 7, 24 and 26, respectively, are operated through differential gear mechanisms 103, 104 and 105, respectively, one end 35 of the differentials being operated synchronously with the belt 11 through the gearing 106, and the other ends of the differentials are driven by the flexible shafts 107, 108 and 109, respectively. Since the planetary gear 40 arrangements for driving these flexible shafts are identical, a description of the one associated with the feeder belt 7 will suffice. The part of this feeder belt on which the material rests while being delivered from 45 the receptacle 6' is supported by the yielding supports 110 to 114 inclusive and the support 112 engages the arm 115 of a lever having a cam slot 116 in its other arm in which a pin attached to the pivoted arm 117 50 slides. At the end of the pivoted arm 117 is located a contact roller 118 freely rotatable with respect to the arm 117 and secured to the flexible shaft 107. This roller 118 is driven by the belt 119 which is operated synchronously with the feeder belt 7 through 55 any suitable gearing. The arrangement of this device is such that when no material is on the feeder belt 7 over the yielding support 112 located in the chute between the receptacle 6' proper and its delivery end, the roller 118 will be in the position at right angles to the direction of movement of the belt 119 and hence will not rotate. The switch contact member 100 will then be 60 moved through the end of the differential 65
- driven by the gearing 106 to make engagement with the contact segment 120 so as to cause the deenergization of all the driving motors and thus stop the conveyer system. The same result is secured when the belt 7 70 stops while the belt 11 continues to run. When the proper weight of material is over the support 112, the switch contact member will be in the position shown in Fig. 6, and when the weight of material exceeds the 75 predetermined maximum, the roller 118 will be moved to the dotted line position of Fig. 5, causing the switch 100 to be moved through the differential to make engagements with the contact 121, thus causing the 80 deenergization of the driving motors and stopping the system.
- When the switch 100 is moved to make engagement with the segment 122, the speed of the motor driving the feeder belt is decreased so as to deliver less material and in case the weight of material is still greater than the predetermined value and the switch 100 is moved to make engagement with contact segment 123, the speed of the motors 90 driving the belts 11 and 14 is increased so as to automatically provide for carrying off this greater amount of material. The contact 124 is provided for increasing the speed of the feeder belts so as to deliver more material from the receptacle. Ordinarily, this switch 100 will oscillate between the contacts 122 and 124 so as to automatically maintain the delivery of a substantially uniform amount of material from the receptacle. 95 The cam slot 116 and the adjustable connection 112' provide means whereby an accurate adjustment of the device may be had. It will be apparent that any preferred form of regulator may be employed.
- 100
- 105
- The drum controller 125 which is moved synchronously with the belt 11, is provided for effecting any predetermined order of delivery of material from the receptacles 6', 86 and 87. This controller is provided with 110 a plurality of stationary contact fingers which are adapted to engage contact segments on the drum and control the energization of the feeder belt motors 8, 25 and 27. Referring to Figs. 7 and 8 which show plan 115 and sectional views, respectively, of the controller drum, the continuous conductor 126 is provided for energizing the drum from the source of supply and the segments 127 for controlling the energization of the 120 motors driving the feeder belts are made up of a plurality of small segments each having a pin adapted to be inserted in rows of holes suitably arranged on the periphery of the drum. By adding or taking off these 125 small segments and by making up segments on the drum of a plurality of these small segments at any desired place around the periphery of the drum, I am able to exactly predetermine the duration of operation of 130

each feeder belt and thus the amount of material delivered from the receptacle, as well as to operate the feeder belts in any predetermined order of succession; thus, the feeder belts 5 may all be operated continuously, a part continuously and others intermittently, or all of them intermittently in any desired order of succession, or any other desired combination.

10. The timing arrangement 128 comprises a switch member which is driven by any suitable constant speed motor such as a clock mechanism, and is adapted to periodically make and break the circuit of the operating 15 coil of the switch 52 when the switch 129 is open, thereby automatically starting and stopping all or the entire part of the conveyer system which has been selected for use and in that way deliver material from 20 the belt 14 in a manner best suited to the particular necessities of the occasion.

The diaphragm circuit controllers 130, one for each of the receptacles 6', 86 and 87, are provided for interrupting the coil circuit 25 of the switch 52 to deenergize the various driving motors being used when the material in any one of the receptacles is less than a predetermined minimum. A sectional view of this device is shown in Fig. 30 9. It comprises a flexible metal diaphragm which is adapted to operate a switch contact member 131 so as to make an electrical contact when the material in the receptacle presses against the diaphragm and to open 35 the contact when the pressure of the material is relieved. Short circuiting switches are provided whereby each of these diaphragm contact makers may be rendered ineffective independently of the others and 40 the switch 132 is provided for rendering all of these devices ineffective.

As thus constructed and arranged the operation of my invention is as follows: With the manual switch 133 thrown to make engagement 45 with its upper set of contacts and all of the other devices in the positions shown in Fig. 4, the operation of my invention is identical with that set forth fully in connection with the arrangement of Fig. 3 50 and it is considered unnecessary to repeat those features of the operation of the complete arrangement. The automatic starting arrangement for the motor 15 has been indicated at 134.

55. Let it be assumed that proper amounts of material of the desired kinds are being supplied to the receptacles 6', 86 and 87 in any suitable manner and that it is desired that the delivery of material shall incorporate 60 some or all of the new features peculiar to Fig. 4. Assume that it is desired to deliver variable amounts of material from the receptacles and at the same time control the speeds of the belts 14 and 11 so as to properly deliver the material supplied from the

receptacles. With the parts in the positions shown in the drawing, by closing the switch 68 and then closing the switch 69, the motors 15 and 12 will be started in succession with the desired time interval, but motors 8, 25 70 and 27 will not start since the controller 61 is in the off position and the other controlling switches have not been closed. The manual switch 134 will now be closed since the control by the lowering bin contacts 75 49, 50 and 51 is not desired for the operation about to be explained. This switch 134 merely short circuits contacts to render the switches 49, 50 and 51 ineffective and thus cause the operating coil for the switch member 52 to be energized to close the contacts 76, 75 and 77, after which the manual switch 68 may be opened. The switch 135 will now be closed so as to control the fields of motors 8, 25 and 27 and the controller 80 85 will now be operated. The line switch 90 for motor 8, line switch 64 for motor 56, and line switch 66 for motor 55, will be energized by moving the contacts 89, 92 and 95, respectively, into engagement with their 90 respective stationary contacts, the coils of these switches receiving energy through the contact 77 associated with the automatic starting and stopping switch 52. The feeder belt 7 will thus be started and the motors 95 25 and 27 will be energized to start the feeder belts 24 and 26, respectively, when the motors 56 and 55, respectively, have lowered the directing chutes 21 and 20. The belts 7 and 24 will be operated at such a 100 speed and the directing chutes 21 and 20 will be so disposed with respect to the belt 11 that these directing chutes will not interfere with the material on the belt 11 which has been delivered from the receptacles 6' and 86. The speeds of the motors 8, 25 and 27 will be varied by moving the arms of the controller 155 so that the contacts 91, 93 and 96 will be so positioned as to include the desired amount of resistance 110 in the shunt fields of the motors and thus deliver the amount of material desired from each of the receptacles. The contacts 97 and 98 will at the same time be automatically moved, so as to vary the 115 resistances in the shunt fields of the motors 12 and 15, respectively, so that the material delivered from the receptacles will be limited as to its maximum by the capacity of the delivery belts 11 and 14 at varying 120 speeds.

Assume that the arms of the controller 155 have been moved to the positions at which the desired amount of material is being delivered from the receptacles and 125 that it is desired that this delivery be automatically maintained. The switch arm 100, of the regulator 99 and the switch arms 101 and 102 of the similar regulators associated with feeder belts 24 and 26 will be adjusted 135

- to their neutral positions, the positions shown on the drawing. After this, the switches 136 and 137 will be closed. The switch 136 controls the circuit for the field rheostats 138, 139 and 140 for the motors 8, 25 and 27, respectively. Each of these rheostats is individually controlled by a motor similar to the motor 141 provided for varying the rheostat 140, but for the sake of clearness the motors for the rheostats 138 and 139 have not been shown. The operation of this arrangement will be explained in connection with the regulator 99, since the operation of this regulator in controlling the motor 141 and the rheostat 140 is similar to the control for the rheostats 138 and 139 which have not been shown but will be readily understood. When the material being delivered from the receptacle 6' is less than the predetermined amount, the switch arm 100 will be moved by the regulator 99 so as to make engagement with the contact 124, the motor 141 will be energized with the field winding 142 in circuit and the rheostat 140 will be moved to increase the resistance in the field of motor 8 and thus increase the speed of this motor so that the feeder belt 7 will deliver more material. In case the material on the belt 7 is greater than the predetermined maximum, the switch arm 100 will be moved to make engagement with the contact 122, thereby energizing the motor 141 with the field winding 143 in circuit, and since this winding is reversely wound to the winding 142, the motor will be operated to decrease the speed of motor 8.
- The closing of the switch 137 connects the regulating rheostats 144 and 145 in the field circuits of the motors 12 and 15, respectively. These rheostats are operated together by the motor 146 having the reversely wound field magnets 147 and 148. When the switch arm of the regulator 99 makes engagement with the contact 123 due to the material on the belt 11 being in excess of the predetermined maximum, the motor 146 is energized with the field 148 in circuit to move the rheostats 144 and 145 to increase the speeds of the motors 12 and 15 to take care of the excess of material being delivered from the receptacles. The motor 146 is operated in the other direction by pressing the push button 149 when the speeds of the belts 11 and 14 can be safely reduced. The switches 101 and 102 of the regulators for the belts 24 and 26 respectively will control the rheostats 144 and 145 in the same manner as the regulator 99.
- After the regulators have been adjusted so as to maintain substantially constant the delivery of material from the receptacles, the switch 150 will be closed, introducing another protective feature. Now, in case the regulator 99 moves the switch arm 100
- into engagement with the contact 120 due to a substantial failure of delivery of material from the receptacle 6', the coil of relay 151 will be energized to pick up its contacts and open the circuit of the coil for switch 42, causing this switch to gradually drop its contacts and stop the various belts in the previously mentioned desired successive relation; that is, the feeder belts first, belt 11, and finally belt 14. The pivoted catch 152 will retain the relay 151 in its upper or open position. In case the switch arm 100 is moved so as to engage the contact 121 due to a weight of material on the belt 7 greatly in excess of the predetermined maximum, the relay 151 will likewise be energized to pick up its contacts and cause the stopping of the belt system. The regulators similar to 99 for the belts 24 and 26 will control the relay 151 in the same manner as the regulator 99.
- The operation of the drum controller 125 for obtaining any predetermined order of operation of the belts will now be explained. Assume that the regulator 99 and the similar regulators for belts 24 and 26 are rendered ineffective for the time being by the opening of the switches 137, 136 and 150 and that it is desired that the amount of material delivered from each receptacle, shall be determined by the length of time its feeder belt operates and that material is to be delivered from the receptacles to the belt 11 in any predetermined order of succession as determined by the length of the segments 127 on the controller 125 and the position of these segments on the drum. The controller 155 will be adjusted to regulate the speeds of the various belts so as to deliver material at the desired rate. The switch 133 will now be closed on its lower set of contacts, the switches 153 and 154 will be opened and the controller 61 will be moved to the position *a*.
- Control of the motors driving the feeder belts is thus given to the drum controller 125 and these feeder belts will be started and stopped in the manner determined by the contact segments 127.
- The opening of the switch 132 will put the diaphragm controllers 130 into operation so that in case the material in any one of the receptacles is reduced to such an extent that the diaphragm associated with that receptacle is permitted to bulge out and open the circuit of the operating coil of switch 52 at the contact 131, the switch 52 will gradually drop and stop the feeder belts first, then belt 11 and finally belt 14. When more material is placed in the receptacle, the diaphragm will automatically close the circuit for the coil of switch 52 and this switch will close its contacts and start the belt 14 first, the belt 11 next and the feeder belt or belts last.

When it is desired that the entire conveyer system or the part selected for use shall be periodically started and stopped, the switch 129 will be opened so as to permit the periodic make and break of the circuit for the operating coil of switch 52, thus opening and closing this switch to start and stop the driving motors.

It will be readily understood that while certain of the features of my invention are operable to effect certain results when other features of my invention are not being used, it will readily be understood that numerous combinations of the arrangements are possible.

For purposes of illustration and an understanding of the principles of my invention I have shown an arrangement for controlling the speeds of the driving motors by the well-known field control method but it will be understood that any of the well-known methods of controlling the speeds of the motors may be used as the particular installation may require.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

I claim as my invention:

1. The combination in a conveyer system of a series of conveyers, means for driving the said conveyers, and a controller for automatically starting the said series in succession beginning with the delivery end of the system and stopping the series in succession in inverse order.

2. The combination in a conveyer system of a series of conveyers, means for driving the conveyers, and means responsive to the delivery of material to the system for automatically starting said series in succession beginning with the delivery end of the system and stopping the series in succession in inverse order.

3. The combination in a conveyer system of a plurality of conveyers arranged in series relation, a separate driving motor for each of said conveyers, an automatic controller for starting and stopping the said driving motors, and connections whereby the conveyers are automatically started in succession beginning with the delivery end and stopped in succession in inverse order, responsive to the delivery and cessation of delivery of material to the system.

4. The combination in a conveyer system of a series of conveyers, means for driving the said conveyers, and a controller and connections whereby the conveyers are started

in a certain succession and stopped in succession in the inverse order.

5. The combination in a conveyer system of feeder and delivery conveyers arranged in series relation, means for driving the conveyers, and a controller for automatically starting the delivery conveyer first, the feeder conveyer second, and automatically stopping the feeder conveyer first and the delivery conveyer second.

6. The combination in a conveyer system of a plurality of conveyers arranged in series relation, separate driving means for each of said conveyers, means for gradually starting the conveyers, and a control for the conveyer system having connections whereby each conveyer is automatically started beginning with the delivery end as each preceding conveyer reaches a predetermined speed, and are automatically stopped in succession as each conveyer beginning at the receiving end stops.

7. The combination in a conveyer system, of feeder, intermediate, and delivery conveyers arranged in series relation, means for driving the said conveyers, and an automatic control for starting the delivery conveyer and bringing this conveyer up to a predetermined operating speed, then starting the intermediate conveyer and bringing this conveyer up to a predetermined operating speed and finally starting the feeder conveyer, the said automatic control having means for automatically stopping the conveyers in succession beginning with the feeder conveyer.

8. The combination in a conveyer system of feeder, intermediate and delivery conveyers arranged in series relation, means for driving the said conveyers, an automatic controller for starting the conveyers in succession beginning with the delivery conveyer and stopping the conveyers in succession beginning with the feeder conveyer, and a manual control for the said automatic controller.

9. The combination in a conveyer system of a plurality of conveyers arranged in series relation, means for driving said conveyers, control for the conveyers for starting the series of conveyers in succession beginning at the delivery end of the system, and automatic means responsive to the cessation of delivery of material to the system for the stopping of the conveyers in inverse order as each conveyer has been fully discharged.

10. The combination in a conveyer system of a plurality of conveyers arranged in series relation, means for driving the said conveyers, means responsive to the delivery of material to the system for automatically starting said series in succession beginning with the delivery end of the system and means responsive to the cessation of de-

- livery of material to the system for automatically stopping the series in succession beginning at the receiving end of the system as each conveyer discharges to the next 5 succeeding conveyer.
11. The combination in a conveyer system, of feeder, intermediate and delivery conveyers arranged in series relation, a controller for automatically starting the conveyers in succession beginning with the delivery end and for automatically stopping the conveyers in succession beginning at the feeder end as each conveyer has been fully discharged.
12. The combination in a conveyer system, of feeder, intermediate and delivery conveyers arranged in series relation, a separate motor for driving each of said conveyers, a control for the driving motors whereby the delivery conveyer is operated at the highest speed, the intermediate conveyer at a lower speed and the feeder conveyer at the lowest speed, and a motor controller operated responsively to the delivery 20 and cessation of delivery of material to the feeder conveyer for starting the motor driving the delivery conveyer first, the intermediate conveyer second and the feeder conveyer last, and stopping the motors successively in inverse order.
13. In a conveyer system, a plurality of conveyers arranged in series relation, the capacity of said conveyers increasing from the feeder to the delivery end of the system, means for driving said conveyers, and automatic means responsive to the delivery of material to the feeder end of the system for varying the speed of the conveyers and preserving a predetermined relation between 35 the capacities of said conveyers.
14. The combination in a conveyer system of a plurality of conveyers arranged in series relation, means for driving each of said conveyers at varying speeds, automatic 40 means responsive to the delivery and cessation of delivery of material to the system for starting and stopping said conveyers, a controller whereby the speed of said conveyers can be varied at will, and connections whereby no conveyer can deliver to the next succeeding belt more material than such conveyer can discharge.
15. In a conveyer system, a plurality of conveyers arranged in series relation, the capacity of said conveyers increasing from the feeder to the delivery end of the system, means for driving said conveyers, and a control for said driving means for varying the relative speed of any selected conveyers 55 of the series and automatically preserving the said order of conveyer capacities increasing from the feeder to the delivery end of the system.
16. In a conveyer system, a plurality of conveyers arranged in series relation, sepa-
- rate driving means for each of said conveyers, means for varying the relative speeds of said conveyers and means for automatically stopping the conveyers in case any conveyer of the series delivers more 70 material to the next succeeding conveyer than such succeeding conveyer can discharge.
17. The combination with a receptacle for material, of means for conveying the material therefrom, and means responsive to the material in the said receptacle for automatically starting, stopping and varying the speed of the conveying means.
18. The combination in a system of conveyers of feeder and delivery conveyers arranged in series relation, means for delivering material to the feeder conveyer and means responsive to delivery of such material to the feeder conveyer for automatically 80 starting, stopping and varying the speed of the conveyers so as to control the amount of material delivered by the system.
19. The combination in a system of conveyers of a plurality of conveyers comprising feeder and delivery conveyers arranged in series relation, means for driving said conveyers, means for delivering material to the feeder conveyer and automatic means responsive to the delivery of such material for varying the speed of the feeder so as to deliver substantially the maximum capacity of the system at varying speeds.
20. The combination with a receptacle for material, of means for conveying material 100 therefrom, comprising feeder and delivery conveyers arranged in series relation, a separate driving motor for each of said conveyers, an automatic controller operated responsively to the material in the receptacle 105 for controlling the driving motors, and connections whereby the driving motors are automatically started and stopped and the speed of the feeder conveyer motor is automatically varied by said controller so as to 110 control the delivery of material from the receptacles.
21. The combination with a receptacle for material, of means for conveying material therefrom, comprising feeder and delivery 115 conveyers arranged in series relation, a separate driving motor for each of said conveyers, and a motor controller operated responsively to the material in the said receptacles for energizing, deenergizing and 120 varying the speeds of said motors to control the operation of said conveyers.
22. The combination with a receptacle for material, of means for conveying material therefrom, comprising feeder and delivery 125 belts arranged in series relation, a separate motor for driving each of the said belts, and a controller for said driving motors having means operated responsively to the material in the receptacle for energizing and deen-

- ergizing the motor driving the feeder belt so as to control the delivery of material from the receptacle.
23. The combination with a receptacle for material, of means for conveying material therefrom, comprising feeder and delivery conveyers arranged in series relation, a separate motor for driving each of said conveyers, and a controller for said driving motor having means operated responsively to the material in the receptacle for energizing, deenergizing and varying the speed of the motor driving the feeder conveyer so as to control the delivery of material from the receptacle.
24. The combination with a receptacle for material, of means for conveying the material therefrom, comprising feeder and delivery conveyers arranged in series relation, means for driving the said conveyers, and means responsive to the material in the receptacle for varying the speed of the feeder conveyer and starting and stopping the said conveyers so as to control the amount of material delivered by the system.
25. The combination with a receptacle for material, of means for conveying the material therefrom, comprising feeder and delivery conveyers arranged in series relation, means for driving the said conveyers, and automatic means for varying the speed of the feeder conveyer and starting and stopping the said conveyers so as to control the amount of material delivered by the system.
26. The combination with a lowering bin and means for raising and lowering the same, of means for conveying material therefrom, comprising feeder, intermediate and delivery conveyers arranged in series relation, means for driving the said conveyers, and means responsive to the raising and lowering of the lowering bin for controlling the operation of the feeder conveyer and thereby controlling the amount of material delivered by said conveyers.
27. The combination with a receptacle for material, of means for conveying material therefrom, comprising feeder and delivery belts arranged in series relation, a separate motor for driving each of the said belts, a diaphragm controller operated by the material in the receptacle, and means whereby the operation of the feeder belt is controlled by the diaphragm controller so as to maintain at least a predetermined amount of material in the said receptacle.
28. The combination with a receptacle for material, of means for conveying the material therefrom, comprising feeder and delivery conveyers arranged in series relation, means for driving the said conveyers, and automatic means for starting said conveyers and varying the speed of the feeder conveyer so as to control the amount of material delivered by the system.
29. The combination with a receptacle for material and means for conveying the material therefrom, comprising feeder and delivery conveyers arranged in series relation, a separate driving motor for each of said conveyers, a diaphragm circuit controller in the walls of the receptacle operated responsively to the material in the receptacle, and connections whereby the driving motors are automatically started and stopped by said diaphragm circuit controller responsively to the material in the receptacle.
30. The combination with a receptacle for material and means for conveying the material therefrom, comprising feeder and delivery conveyers arranged in series relation, a separate motor for driving each of said conveyers, a circuit controller in the walls of the receptacle for automatically starting and stopping the driving motors responsively to the material in the receptacle, and a controller operated responsively to the weight of the material on the feeder conveyer for controlling the speed of the feeder conveyer.
31. The combination in a conveyer system of feeder, intermediate, and delivery conveyers arranged in series relation, a separate driving motor for each of said conveyers, an automatic controller for the motors operated responsively to the weight of material on the feeder conveyer, and connections whereby the conveyers are stopped in succession beginning with the feeder conveyer.
32. The combination with a receptacle for material, of means for delivering material therefrom, comprising feeder, intermediate, and delivery conveyers arranged in series relation, means for driving said conveyers, and means automatically operated responsively to the material in the said receptacle for starting the conveyers in succession beginning with the delivery conveyer and stopping the said conveyers in succession beginning with the feeder conveyer.
33. The combination with a lowering bin and means for raising and lowering the same, of means for conveying material therefrom, comprising feeder and delivery conveyers arranged in series relation, a separate motor for driving each of the said conveyers, a motor controller operated responsively to the raising and lowering of the lowering bin, and connections whereby the operation of the feeder conveyer is started and stopped responsively to the lowering and raising of said bin.
34. The combination with a lowering bin and means for raising and lowering the same, of means for conveying material therefrom, comprising a plurality of conveyers arranged in series relation, a separate motor for driving each of the said conveyers, a motor controller operated responsively to

the raising and lowering of the lowering bin having connections whereby the conveyers are started and stopped responsively to the lowering and raising of the lowering bin.

- 5 35. The combination with a lowering bin and means for raising and lowering the same, of means for conveying material therefrom, comprising feeder, intermediate and delivery conveyers arranged in series 10 relation, a separate motor for driving each of said conveyers, and a motor controller operated responsively to the raising and lowering of the lowering bin for starting the motor driving the delivery conveyer first, 15 the intermediate second, the feeder conveyer last and stopping the motors successively in inverse order.

36. The combination with a lowering bin, of means for raising and lowering the same, 20 means for conveying material therefrom, comprising feeder, intermediate and delivery conveyers arranged in series relation, a separate motor for driving each of said conveyers, a control for the driving motors 25 whereby the delivery conveyer is operated at the highest speed the intermediate conveyer at the next highest speed and the feeder conveyer at the lowest speed, and a motor controller operated responsively to 30 the raising and lowering of the lowering bin for starting the motor driving the delivery conveyer first, the intermediate conveyer second, and the feeder conveyer last, and stopping the motors successively in inverse 35 order.

37. The combination with a receptacle for material, and a lowering bin for delivering material thereto, of feeder, intermediate, and delivery conveyers for delivering material 40 from the receptacle, driving means for the said conveyers, manually controlled means for starting the delivery conveyer first, and then the intermediate conveyer, and means 45 for automatically starting the feeder conveyer responsively to the lowering of the lowering bin.

38. The combination with a receptacle for material and a lowering bin for delivering material thereto, of feeder, intermediate, and delivery conveyers for delivering material 50 from the receptacle, manually controlled automatic means for starting the delivery conveyer and then the intermediate conveyer, and means independent of the said 55 manually controlled automatic means and operated responsively to the lowering of the lowering bin for starting the feeder conveyer, and operated responsively to the elevation of the lowering bin for stopping the 60 conveyers in succession beginning with the feeder conveyer.

39. The combination with a lowering bin and a receptacle for material into which the bin discharges, of feeder, intermediate, and 65 delivery conveyers for delivering material

from the receptacle, means for driving the said conveyers, manually controlled means for automatically starting the conveyers in succession beginning with the delivery conveyer and stopping the conveyers in succession beginning with the feeder conveyer, and automatic means controlled by the lowering bin for starting and stopping the said conveyers in the succession named.

- 70 40. The combination with a receptacle for material and a lowering bin for delivering material thereto, of feeder and delivery conveyers for delivering material from the receptacle, driving means for the said conveyers, manually controlled means for starting the delivery conveyer, and means for automatically starting the feeder conveyer responsively to the lowering of the lowering bin after the delivery conveyer has been 80 started.

- 85 41. The combination with a lowering bin, of means for delivering material therefrom, comprising feeder, intermediate and delivery conveyers arranged in series relation, a separate driving motor for each of said 90 conveyers, and means automatically operated responsively to the material in the lowering bin for starting the motor driving the delivery conveyer first, the intermediate second, the feeder conveyer last, and 95 stopping the said motors successively in the inverse order.

42. The combination with a receptacle for material, of means for conveying the material therefrom, comprising feeder and delivery conveyers arranged in series relation, means for driving the said conveyers, and automatic means for energizing the said driving means so as to start the conveyers in 100 succession beginning with the delivery conveyer, and for stopping the said conveyers in succession beginning with the feeder conveyer, and means coöperating with the said automatic means and responsive to the material in said receptacle for maintaining an 105 amount of material in the receptacle and fully discharging the material from the delivery conveyer.

- 110 43. The combination in a conveyer system of a plurality of conveyers arranged in series 115 relation, means for driving the conveyers, and means responsive to the delivery of material to the system for automatically starting the series in succession beginning with the delivery end and upon the cessation of delivery of material to the system stopping the conveyers in succession beginning at the receiving end after each conveyer has discharged its material.

- 120 44. The combination with a receptacle for material, of a conveyer for delivering material therefrom, means for driving said conveyer and automatic means for retaining a predetermined amount of material in said receptacle and stopping said conveyer after 125 130

- the material on the conveyer has been fully discharged.
45. The combination with a plurality of receptacles for material, of a feeder conveyer for each of said receptacles for delivering material therefrom, means automatically operated responsively to the material in one of said receptacles for controlling a portion of said feeder conveyers, and means for selecting the feeder conveyers to be subjected to the said automatic operation.
46. The combination with a receptacle for material, of means for conveying the material therefrom, comprising feeder and delivery conveyers arranged in series relation, means for driving the said conveyers, and automatic means controlled by the material in the receptacle for stopping the feeder conveyer and thereafter stopping the delivery conveyer after the material has been fully discharged from the delivery conveyer.
47. The combination in a conveyer system of a feeder, intermediate, and delivery conveyers arranged in series relation, means for driving the said conveyers and an automatic controller for starting the conveyers in succession beginning with the delivery conveyer and for stopping the feeder conveyer first, the intermediate conveyer next after the material on such conveyer has been fully discharged to the delivery conveyer, and finally stopping the delivery conveyer when the material on this conveyer has been fully discharged.
48. The combination with a plurality of receptacles for material, of a feeder conveyer for each of said receptacles for delivering material therefrom, a delivery conveyer for delivering material from the feeder conveyers, and means automatically operated responsively to the material in a portion of said receptacles for controlling the feeder conveyers so as to maintain a substantially constant delivery of material from the delivery conveyer.
49. The combination with a plurality of receptacles for material, of a conveyer for delivering material from the said receptacles, and means automatically operated responsively to the material in a portion of said receptacles for maintaining a substantially constant delivery of material from said receptacles to said delivery conveyer.
50. The combination with a plurality of receptacles for material, of a feeder conveyer for each of said receptacles for delivering material therefrom, a separate motor for driving each of said conveyers, a motor controller in each of said receptacles operated responsively to the material in the receptacles, and connections whereby the driving motors are stopped when the material in any one of the receptacles is less than a predetermined minimum.
51. The combination with a plurality of receptacles for material, of a conveyer for delivering material therefrom, and means automatically operated responsively to a cessation of delivery of material from a portion of the receptacles to the said conveyer for controlling the delivery of material from the receptacles so as to maintain a substantially constant delivery of material from the conveyer.
52. The combination with a plurality of receptacles for material, of a feeder conveyer for each of said receptacles, a separate motor for driving each of said feeder conveyers, and a controller for automatically energizing and deenergizing the said driving motors to operate the feeder conveyers at predetermined intervals.
53. The combination with a plurality of receptacles for material, of a feeder conveyer for each of said receptacles for delivering material therefrom, a delivery conveyer for delivering material from the feeder conveyers, and means automatically operated responsively to a cessation of delivery of material from a portion of the receptacles to the delivery conveyer for controlling the feeder conveyers so as to maintain a substantially constant delivery of material from the delivery conveyer.
54. The combination with a plurality of receptacles for material, of a feeder, intermediate and delivery conveyers arranged in series relation, means for driving the conveyers, a controller for the conveyers for automatically starting the conveyers in succession beginning with the delivery conveyer and automatically stopping the conveyers beginning with the feeder conveyer, and means for automatically controlling the conveyers so as to maintain a constant delivery of material from the delivery conveyer.
55. The combination with two receptacles for material, of a feeder conveyer for each of said receptacles for delivering material therefrom, a delivery conveyer for delivering material from the feeder conveyer, separate driving motors for each of said conveyers, a controller for the feeder conveyer driving motors, and connections whereby the motor driving the first feeder conveyer is automatically stopped and the motor driving the second feeder conveyer is automatically started so as to maintain a substantially constant delivery of material from the delivery conveyer.
56. The combination with a plurality of receptacles for material, of a feeder conveyer for each of said receptacles, a separate motor for driving each of said feeder conveyers, a controller for automatically energizing and deenergizing said driving motors to operate the feeder conveyers at predetermined intervals, and a controller

for selecting at will the feeder conveyer driving motors to be thus automatically energized and deenergized.

57. The combination with a lowering bin and two receptacles for material, the first of the receptacles receiving material from the lowering bin, of a feeder conveyer for each of said receptacles, a delivery conveyer for delivering material from the feeder conveyers separate driving motors for each of said conveyers, a controller for the motor driving the feeder conveyer of the first receptacle operated responsively to the raising and lowering of the lowering bin, and connections whereby the feeder conveyer associated with the first receptacle is automatically stopped and started responsive to the raising and lowering of the lowering bin, and the feeder conveyer associated with the second receptacle is started and stopped responsively to the stopping and starting respectively of the first feeder conveyer.

58. The combination with two receptacles for material, of a feeder conveyer for each of said receptacles for delivering material therefrom, a delivery conveyer for delivering material from the feeder conveyers separate driving motors for each of said conveyers, a controller for the feeder conveyer driving motors operated responsively to the delivery and cessation of delivery of material to one feeder conveyer, and connections whereby the feeder conveyer associated with the second receptacle is started and stopped responsively to the stopping and starting respectively of the first feeder conveyer so as to maintain a constant delivery of material from the delivery conveyer.

59. The combination with two receptacles for material, a feeder conveyer for each of the receptacles for delivering material therefrom, and a controller for the feeder conveyers operated responsively to the cessation of delivery of material to one of the receptacles for automatically stopping the feeder conveyer associated with this receptacle and starting the feeder conveyer associated with the other receptacle.

60. The combination with a receptacle for material, of a feeder conveyer and a delivery conveyer for delivering material therefrom, means for driving the said conveyers, an automatic controller for the said driving means jointly controlled by the feeder and the delivery conveyers, and varying means for varying the speed of the said feeder conveyer so as to maintain a substantially constant delivery of material from the receptacle.

61. The combination in a conveyer system of feeder and delivery conveyers arranged in series relation, driving motors for said conveyers, manually controlled means

for starting the delivery conveyer, means coöperative with the feeder and delivery conveyer for automatically stopping and starting said feeder responsive to the delivery and cessation of delivery of material to the feeder conveyer so long as said delivery conveyer continues to run.

62. The combination in a conveyer system, of a delivery conveyer, a feeder for delivering material thereto, and an automatic controller controlled by said feeder and delivery conveyers jointly for controlling the delivery of material by said feeder so as to limit the delivery of said material to the maximum capacity of the delivery conveyer.

63. The combination with a plurality of receptacles for material, of a feeder conveyer for each of said receptacles for delivering material therefrom, means for varying at will the speed of each of said conveyers independently of the other conveyers, and means automatically operated responsive to the material in a portion of said receptacles for controlling the delivery of material from the feeder conveyers.

64. The combination in a conveyer system of a plurality of feeder and a plurality of delivery conveyers, means for driving each of said conveyers at varying speeds, automatic means coöperative with the feeder and the delivery conveyers for varying the speed of the feeder conveyers so as to control the amount of material delivered by the system and connections with said automatic means for controlling the varying speed of the conveyers whereby no delivery conveyer can deliver to the next succeeding conveyer more material than such conveyer can discharge.

65. The combination in a conveyer system, of feeder, intermediate and delivery conveyers arranged in series relation, means for driving the said conveyers, a controller for automatically starting the conveyers in succession beginning with the delivery conveyer and stopping the conveyers in succession beginning with the feeder conveyer, and means for independently varying the speed of the feeder conveyer so as to vary the amount of material delivered by the system.

66. The combination with a plurality of receptacles for material, of a feeder conveyer for each of said receptacles for delivering material therefrom, and a controller and connections for simultaneously varying the speeds of the said feeder conveyers so as to vary the amounts of material delivered from the said plurality of receptacles, the said controller having means for selecting at will the feeder conveyers to be thus controlled.

67. The combination with a plurality of receptacles for material, of a feeder con-

- veyer for each of said receptacles for delivering material therefrom, a separate driving motor for each of said feeder conveyers, means for varying at will the speed of each 5 of the driving motors independently of the other motors, a controller for the driving motors in each of said receptacles operated responsively to the material in the receptacle, and connections whereby the said driving 10 motors are automatically started and stopped responsively to the material in the receptacles.
68. The combination with receptacle means for material, of a plurality of feeder 15 conveyers and a delivery conveyer for delivering material therefrom, means for varying the speeds of the feeder conveyers so as to vary the amount of material delivered to the delivery conveyer, means for 20 varying the speed of the delivery conveyer, and an automatic controller operated responsively to the speeds of the feeder and delivery conveyers for varying the speeds of the feeder conveyers so as to limit the delivery 25 of material to the delivery conveyer to the capacity of the delivery conveyer at varying speeds.
69. The combination with a plurality of receptacles for material, of a feeder conveyer for each of said receptacles and a delivery conveyer for delivering material from the feeder conveyers, a separate driving motor for each of said conveyers, means for starting and stopping the feeder conveyer 30 driving motors so as to deliver material from the receptacles in any predetermined manner, and a controller for the driving motors having means for varying the speed of each of the feeder conveyer driving motors 35 independently of the other feeder conveyer motors and having means for proportionately and simultaneously varying the speed of the delivery conveyer driving motor.
70. The combination in a conveyer system 40 of a plurality of feeder conveyers and a delivery conveyer for delivering material from the feeder conveyer, a separate driving motor for each of the conveyers, a controller for the feeder conveyer driving motors having means for starting and stopping the 45 feeder conveyer driving motors for predetermined intervals and in any predetermined order of succession, and a controller for the driving motor having means for 50 varying the speed of each of the feeder conveyer driving motors independently of the other feeder conveyer motors and having means for proportionately and simultaneously varying the speed of the delivery 55 conveyer driving motor.
71. The combination in a conveyer system, of a plurality of feeder conveyers, a delivery conveyer for delivering material from the said feeder conveyers, a manual 60 controller for selecting the feeder convey- 65 ers to be operated, means for controlling the feeder conveyers selected so as to deliver a predetermined amount of material in any predetermined order from the selected feeder conveyers to the delivery conveyer, 70 and automatic means operated responsively to the feeder and the delivery conveyers for limiting the amount of material delivered to the delivery conveyer to the capacity of the delivery conveyer. 75
72. The combination with a plurality of receptacles for material, of a conveyer for delivering material from said receptacles, means for automatically delivering material from the said receptacles to the said conveyer at predetermined intervals, and a controller for selecting at will the receptacles to be subjected to the said automatic operation. 80
73. The combination with a plurality of receptacles for material, of a conveyer for delivering material from said receptacles, means for driving said conveyer, means for automatically delivering material simultaneously from the said receptacles to the said conveyer at predetermined intervals, and a controller for selecting at will the receptacles to be subjected to the said automatic operation. 85
74. The combination with a plurality of receptacles for material, of a conveyer for delivering material from said receptacles, means for driving said conveyer, means for automatically delivering material in a predetermined order from the said receptacles to the said conveyer at predetermined intervals, and a manually operated controller for selecting at will the receptacles to be subjected to the said automatic operation. 90
75. The combination with a plurality of receptacles for material, of a conveyer for delivering material from the said receptacles, means for driving said conveyer, means for automatically delivering material successively from the said receptacles to the said conveyer at predetermined intervals, and a controller for selecting at will the receptacles to be subjected to the said automatic operation. 105
76. The combination with a plurality of receptacles for material, of a conveyer for delivering material from said receptacles, means for driving the said conveyer, means for automatically delivering material from said receptacles in a predetermined order to the said conveyer at predetermined intervals, and a controller for selecting at will the receptacles to be subjected to the said automatic operation. 110
77. The combination with a plurality of receptacles for material, of a conveyer for delivering material from said receptacles, means for driving said conveyer, means for controlling the amount of material delivered from the individual receptacles so as to au- 115
- 120
- 125
- 130

tomatically deliver material continuously or successively or intermittently, or in a predetermined manner from the said receptacles to the said conveyer, and means for varying 5 at will the amount of material proportionately thus delivered from said receptacles to said conveyer.

78. The combination with a receptacle for material, of a feeder conveyer, a delivery 10 conveyer, movable directing means for conducting the material from the feeder conveyer to the delivery conveyer, and means for controlling the operation of the feeder conveyer responsively to the operation of 15 the directing means.

79. The combination with a receptacle for material, of a feeder conveyer, a delivery 20 conveyer directing means for conducting the material from the feeder conveyer to the delivery conveyer, means for lowering the said directing means into coöperative relation with the delivery conveyer and for elevating the directing means out of the coöperative relation, and means operated 25 responsively to the operation of the directing means for controlling the operation of the feeder conveyer.

80. The combination with a receptacle for material, of a feeder conveyer, a delivery 30 conveyer, means for directing the flow of material from the feeder conveyer to the delivery conveyer, the said means normally biased to an elevated position above the delivery conveyer, and means for lowering 35 the said directing means to the delivery conveyer and automatically starting the feeder conveyer so as to deliver material to the delivery conveyer.

81. The combination with a receptacle for 40 material, of a feeder conveyer and a motor for driving the same, means for directing the flow of material from the feeder conveyer to the delivery conveyer, the said means normally biased to an elevated position above the delivery conveyer, a motor for lowering the said directing means to the delivery conveyer, and means operated 45 responsively to the lowering of the directing means for energizing the motor driving the feeder conveyer.

82. The combination with a plurality of 50 receptacles for material, of a conveyer for delivering material from the said receptacles, means for driving said conveyer, means for controlling the amount of material delivered from the individual receptacles so as to automatically deliver material continuously or successively or intermittently or in a predetermined manner to said conveyer at 55 predetermined intervals, and means for selecting at will the receptacles to be subjected to said automatic operation.

83. The combination with a plurality of 60 receptacles for material, of a conveyer for delivering material from the said recep-

tacles, means for driving said conveyer, means for controlling the amount of material delivered from the individual receptacles so as to automatically deliver material continuously or successively or intermittently or in a predetermined manner to said conveyer at predetermined intervals, means for selecting at will the receptacles to be subjected to said automatic operation, and a controller with connections for varying 75 the amount of material so delivered responsive to the varying speed of the delivery conveyer,

84. The combination with a plurality of receptacles for material, of a feeder conveyer for each of said receptacles, a separate motor for driving each of said feeder conveyers, a controller for automatically varying the speeds of the driving motors so as to maintain the delivery of a predetermined 80 amount of material from the receptacles, and a controller for selecting at will the feeder conveyer driving motors to be thus automatically controlled.

85. The combination with a plurality of 85 receptacles for material, of a feeder conveyer for each of said receptacles, a separate motor for driving each of said feeder conveyers, a controller for automatically energizing and deenergizing the said driving 90 motors to operate the feeder conveyers at predetermined intervals, a controller for automatically varying the speeds of the motors driving the feeder conveyers so as to maintain the delivery of a predetermined 95 amount of material from the receptacles, and a controller for selecting at will the feeder conveyer driving motors to be thus automatically controlled.

86. The combination with a plurality of 100 receptacles for material, of a feeder conveyer for each of said receptacles, a delivery conveyer for delivering material from the feeder conveyers, and a controller operating synchronously with the delivery conveyer for automatically controlling the operation of the feeder conveyers.

87. The combination with a plurality of 105 receptacles for material, of a feeder conveyer for each of said receptacles, a separate 110 motor for driving each of said feeder conveyers, and a controller operated synchronously with the delivery conveyer and having adjustable means thereon for energizing and deenergizing the feeder conveyer driving 115 motors in any predetermined order.

88. The combination with a plurality of 120 receptacles for material, of a feeder conveyer for each of said receptacles, a delivery conveyer for delivering material from the feeder conveyers and a controller operated 125 responsively to the speed of the delivery conveyer and the speeds of the feeder conveyers for controlling the delivery of material from the receptacles.

89. The combination with a plurality of receptacles for material, of a feeder conveyer for each of said receptacles, a delivery conveyer for delivering material from the feeder conveyers and a controller operated responsively to the speed of the delivery conveyer and the speeds of the feeder conveyers for maintaining the delivery of any predetermined amount of material from the receptacles.

90. The combination with a plurality of receptacles for material, of a feeder conveyer for each of said receptacles, a delivery conveyer for delivering material from the feeder conveyers, a controller operated responsively to the speed of the delivery conveyer and the speeds of the feeder conveyers for automatically controlling the delivery of material from the receptacles, and a controller for selecting at will the feeder conveyers to be controlled by the first named controller.

91. The combination with a receptacle for material, of a movable feeder conveyer, a movable delivery conveyer, movable directing means for conducting the material from the feeder conveyer to the delivery conveyer, and means for stopping the feeder conveyer responsively to the elevation of the directing means out of operative relation with the delivery conveyer.

92. The combination with a receptacle for material, of a feeder conveyer and a motor for operating the same, a delivery conveyer and a motor for operating the same, means for directing the flow of material from the feeder conveyer to the delivery conveyer and a motor for moving the directing means into and out of operative relation with the delivery conveyer, and means for energizing the motor driving the feeder conveyer responsively to the operation of the directing means.

93. The combination with a receptacle for material, of a feeder conveyer and a motor for operating the same, a delivery conveyer and a motor for operating the same, means for directing the flow of material from the feeder conveyer to the delivery conveyer and a motor for moving the said directing means into and out of operative relation with the delivery conveyer, and means for energizing the motor driving the feeder conveyer responsively to the lowering of the directing means into operative relation with the delivery conveyer.

94. The combination with a receptacle for material, of a feeder conveyer and a motor for operating the same, means for directing the flow of material from the feeder conveyer to the delivery conveyer and a motor for moving the directing means into and out of operative relation with the delivery conveyer, and means operated responsively to the elevation of the directing means out

of operative relation with the delivery conveyer for deenergizing the motor driving the feeder conveyer.

95. The combination with a receptacle for material, of a feeder conveyer and a motor for operating the same, means for directing the flow of material from the feeder conveyer to the delivery conveyer and a motor for moving the directing means into and out of operative relation with the delivery conveyer, and means for controlling the operation of the feeder conveyer responsively to the operation of the directing means so as to energize the motor driving the feeder conveyer when the directing means is lowered into said operative relation and deenergize the motor driving the feeder conveyer when the directing means is elevated out of said operative relation.

96. The combination with receptacle means for material, of a feeder conveyer, a delivery conveyer, means for directing the flow of material from the feeder conveyer to the delivery conveyer, the said means being movable into and out of operative relation with the delivery conveyer, and means operated responsively to the material in the receptacle means for controlling the operation of the directing means.

97. The combination with receptacle means for material, of a feeder conveyer, a delivery conveyer, means for directing the flow of material from the feeder conveyer to the delivery conveyer, the said means being movable into and out of operative relation with the delivery conveyer, and means operated responsively to the material in the receptacle means for controlling the operation of the directing means and the feeder conveyer.

98. The combination with a receptacle means for material, of a feeder conveyer, a delivery conveyer, means of directing the flow of material from the feeder conveyer to the delivery conveyer, the said means being movable into and out of operative relation with the delivery conveyer, and automatic means for elevating the directing means out of operating relation with a delivery conveyer and stopping the feeder conveyer when the amount of material in the receptacle means is less than the predetermined minimum.

99. The combination with receptacle means for material of a feeder conveyer, a delivery conveyer, means of directing the flow of material from the feeder conveyer to the delivery conveyer, the said means being movable into and out of operative relation with the delivery conveyer, and means for stopping the feeder conveyer and elevating the directing means out of operative relation with the delivery conveyer, responsively to the material in the receptacle means so as to maintain an amount of material in the receptacle means.

100. The combination with a receptacle means for material, of a feeder conveyer, a delivery conveyer, means of directing the flow of material from the feeder conveyer to the delivery conveyer, the said means being movable into and out of operative relation with the delivery conveyer, and automatic means operated responsively to the amount of material in the receptacle means 5 to the delivery conveyer, the said means being movable into and out of operative relation with the delivery conveyer, and automatic means operated responsively to the amount of material in the receptacle means 10 for lowering the directing means into operative relation with the delivery conveyer and starting the feeder conveyer when the amount of material in the receptacle means is greater than a predetermined minimum, 15 and elevating the directing means out of operative relation with the delivery conveyer and stopping the feeder conveyer when the amount of material in the receptacle means has been reduced to the predetermined minimum. 20

101. The combination with a plurality of receptacles for material, of a feeder conveyer for each of said receptacles, a delivery conveyer for delivering material from the 25 feeder conveyers, means for directing the flow of material to the delivery conveyer from the feeder conveyer associated with one of said receptacles, and means automatically operated responsively to the material 30 in another of said receptacles for controlling the operation of the directing means and the feeder conveyer associated with the said one of said receptacles.

102. The combination with a plurality of 35 receptacles for material, of a feeder conveyer for each of said receptacles, a delivery conveyer for delivering the material from the feeder conveyer, means for directing the flow of material to the delivery conveyer from the feeder conveyer associated with one of said receptacles, and means automatically operated responsively to the material in another of said receptacles for controlling the operation of the directing 40 means and the feeder conveyers.

103. The combination with a plurality of receptacles for material, of a feeder conveyer for each of said receptacles, a delivery conveyer for delivering the material 50 from the feeder conveyers, means for directing the flow of material to the delivery conveyer from the feeder conveyers associated with the receptacles and means operated responsively to the material in one or 55 more selected receptacles, for controlling the operation of the directing means and the feeder conveyers associated with one or more selected receptacles, so as to deliver in any predetermined manner from said receptacles. 60

104. The combination in a conveyer system of a series of conveyers, and separate driving motor for each of said conveyers, means for varying the speeds of said driv-

ing motors so that the conveyer speeds will 65 vary from the delivery conveyer as a maximum to the feeder conveyer as a minimum, means for varying the speeds of all the conveyers in the system simultaneously while preserving the said relation of conveyer 70 speeds, and means for energizing the said driving motors to start the said conveyers in a certain succession and stop the conveyers in succession in the inverse order.

105. The combination in a conveyer system, of feeder, intermediate, and delivery conveyers arranged in series relation, means for driving the said conveyers at speeds varying from the speed of the delivery conveyer as a maximum to the speed of the 80 feeder conveyer as a minimum, means for varying at will the speeds of said conveyers while preserving the said relation of conveyer speeds, and means for automatically starting the said conveyers in succession beginning with the delivery conveyer and stopping the said conveyers in succession beginning with the feeder conveyer. 85

106. The combination with a receptacle for material, of feeder, intermediate, and delivery conveyers arranged in series relation, a separate driving motor for each of said conveyers, means for independently varying the speeds of said driving motors so that the conveyer speeds will increase from the 95 feeder to the delivery end of the system, means for varying at will the speeds of said driving motors while preserving the said relation of conveyer speeds, and means automatically operated responsively to the material in the receptacle for starting the conveyers in succession beginning with the delivery conveyer and stopping the conveyers in succession beginning with the feeder conveyer. 100

107. The combination with a receptacle for material, of means for delivering material therefrom, comprising feeder, intermediate, and delivery conveyers arranged in series relation, means for driving the said 110 conveyers, means for automatically starting the conveyers in succession beginning with the delivery conveyer and stopping the conveyers in succession beginning with the feeder conveyer, and means automatically 115 operated responsively to the material in the receptacle for controlling the starting and stopping of the conveyers so as to maintain at least a predetermined amount of material in the receptacle. 120

108. The combination with a receptacle for material, means for conveying the material therefrom, comprising feeder and delivery conveyers arranged in series relation, means for driving the said conveyers, and means automatically operated responsively to the material in the said receptacle for starting the delivery conveyer and after an 125

interval of time, starting the feeder conveyer, and stopping the conveyers in the inverse order of succession.

109. The combination with a receptacle for material, of means for conveying the material therefrom, comprising feeder and delivery conveyers arranged in series relation, a separate driving motor for each of said conveyers, and means automatically operated responsively to the material in the said receptacle for energizing the motor driving the delivery conveyer and after an interval of time energizing the motor driving the feeder conveyer, and deenergizing the said motors in the inverse order of succession.

110. The combination with a receptacle for material, of means for conveying the material therefrom, comprising feeder and delivery conveyers arranged in series relation, a separate driving motor for each of said conveyers, and means controlled by the material in the receptacle for automatically energizing the motor driving the delivery conveyer, and after an interval of time, the motor driving the feeder conveyer, and for stopping the said conveyers in succession beginning with the feeder conveyer when the material in the said receptacle is less than a predetermined minimum.

111. The combination with a receptacle for material, of means for delivering the material therefrom, comprising feeder and delivery conveyers arranged in series relation, means for driving the said conveyers, and means automatically operated responsively to the material in said receptacle, for stopping the feeder conveyer and stopping the delivery conveyer an interval of time thereafter, determined by the length of time necessary to discharge the material from the delivery conveyer.

112. The combination with a receptacle for material, of means for delivering the material therefrom, comprising feeder and delivery conveyers arranged in series relation, means for driving the said conveyers, means for starting the said conveyers in succession beginning with the delivery conveyer and stopping the conveyers in the inverse order of succession, means controlled by the material in the receptacle for preserving a predetermined amount of material in the receptacle, and means whereby the delivery conveyer is stopped after the feeder conveyer, an interval of time determined by the time necessary to discharge the material from the delivery conveyer.

113. The combination with two receptacles for material, of a feeder conveyer for each of said receptacles for delivering material therefrom, and means automatically operated responsively to the material in one of the receptacles for stopping the feeder conveyer associated with that receptacle, and starting the feeder conveyer associated with the other receptacle.

114. With a combination of two receptacles for material, of a feeder conveyer for each of said receptacles for delivering material therefrom, means automatically operated responsively to the stopping of one of the feeder conveyers, for starting the other feeder conveyer, a predetermined interval of time after the stopping of the first feeder conveyer.

115. The combination with two receptacles for material, of a feeder conveyer for each of said receptacles for delivering material therefrom, a delivery conveyer for delivering material from both feeder conveyers and means operated automatically responsively to the material in the first receptacle for stopping the feeder conveyer associated with that receptacle, and starting the feeder conveyer associated with the second receptacle when the last of the material on the delivery conveyer supplied by the first feeder conveyer has reached the second feeder conveyer.

116. The combination with a plurality of receptacles for material, of a feeder conveyer for delivering material from each of said receptacles, and automatic means for starting the feeder conveyer associated with one of the receptacles when the material in another of the receptacles is less than a predetermined minimum.

117. The combination with a receptacle for material and a lowering bin for delivering material thereto, of feeder, intermediate, and delivery conveyers for delivering material from the receptacle, a second receptacle, and a feeder conveyer for delivering material therefrom, a delivery chute associated with this second receptacle, means for driving the said conveyers, and automatic means controlled by the lowering bin for stopping the first feeder conveyer and lowering the delivery chute and starting the second feeder conveyer when the material on the intermediate conveyer has passed beyond the delivery chute.

118. The combination with a receptacle for material, of feeder, intermediate, and delivery conveyers arranged in series relation, means for driving the said conveyers, means for automatically starting the conveyers in succession beginning with the delivery conveyer at speeds varying from the speed of the delivery conveyer as a maximum to the speed of the feeder conveyer as a minimum, the said means automatically stopping the feeder conveyer first, then the intermediate and delivery conveyers in succession as the material on these conveyers is fully discharged, and means for maintaining a substantially constant delivery of material from the delivery conveyer and limiting the delivery of such material to the

maximum capacity of the delivery conveyer at varying speeds.

119. The combination with a receptacle for material, of feeder, intermediate, and delivery conveyers arranged in series relation, means for driving said conveyers, means operative when the material in the receptacles is more than a predetermined minimum for automatically starting the conveyers in succession beginning with the delivery conveyers at speeds varying from the speeds of the delivery conveyer as a maximum to the speed of the feeder conveyer as a minimum, the said means automatically operating when the material in the receptacle is less than the predetermined minimum to stop the feeder conveyer first, then the intermediate and delivery conveyers in succession as the material on these conveyers is fully discharged, and means for maintaining a constant delivery of material from the delivery conveyer and limiting the delivery of such material to the maximum capacity of the delivery conveyer at varying speeds.

120. The combination in a conveyer system of feeder, intermediate and delivery conveyers, means for driving the same, means for automatically starting the said conveyers in succession beginning at the delivery end and stopping said conveyers in inverse order after each conveyer has fully discharged its material, means for automatically operating each conveyer substantially at capacity responsive to the amount of material delivered by the feeder conveyer, connections whereby no conveyer can deliver more material to the next succeeding conveyer than said succeeding conveyer can discharge and means responsive to the delivery of material to the system for automatically maintaining a substantially constant delivery of a predetermined amount of material from the system.

121. The combination in a conveyer system, of a series of conveyers, means for driving the said conveyers, a control for the conveyers for starting the said series in succession beginning with the delivery end of the system, and stopping the series in succession in inverse order, and automatic means with connections whereby no conveyer in the system is operated at greater speed than is necessary to discharge the material delivered to it by the preceding conveyer.

122. The combination in a conveyer system, of a plurality of conveyers arranged in series relation, means for driving said conveyers, and a controller with connections whereby no conveyer of the system can operate at a greater speed than is necessary to fully discharge the material delivered to it by the preceding conveyer and means for varying the amount of material delivered by the system.

123. The combination in a conveyer sys-

tem, of feeder, intermediate, and delivery conveyers, means for driving the same, means for automatically starting the said conveyers in succession beginning at the delivery end and stopping said conveyers in inverse order after each conveyer has fully discharged its material, means for automatically operating each conveyer at a speed no greater than is necessary to fully discharge the material delivered to said conveyer and means responsive to the delivery of material to the system of automatically maintaining a substantially constant delivery of a predetermined amount of material from the system.

124. The combination in a conveyer system, of a plurality of feeder conveyers, a plurality of delivery conveyers arranged in series relation, means for driving said delivery conveyers, separate motors for driving each of said feeder conveyers, and a control for said motors having connections for automatically maintaining a substantially constant delivery of a predetermined amount of material from each of said feeders to the delivery conveyers.

125. The combination in a conveyer system, of a plurality of feeder conveyers, a delivery conveyer for delivering material therefrom, means for driving the delivery conveyer, separate motors for driving each of said feeder conveyers, and a control for said motors having connections whereby all the conveyers in the system are automatically stopped responsive to the delivery of more than a predetermined amount of material by the feeder conveyers.

126. The combination in a conveyer system of a feeder conveyer and a delivery conveyer for delivering material therefrom, means for driving said conveyers, automatic means whereby the speed of the delivery conveyer is varied to vary the amount of material delivered to the delivery conveyer by the feeder conveyer and manually controlled means whereby the speed of the delivery conveyer is automatically varied responsive to the amount of material delivered by the feeder conveyer.

127. The combination in a conveyer system of a plurality of feeder conveyers, a plurality of delivery conveyers arranged in series relation, means for driving said conveyers, automatic means whereby the speed of the feeder conveyers is varied to vary the amount of material delivered to the system, and manually controlled means whereby the speed of the delivery conveyer is automatically varied responsive to the amount of material delivered by the feeder conveyers.

128. The combination in a conveyer system of a feeder conveyer a delivery conveyer for delivering material therefrom, means for driving said conveyers, and automatic means responsive to the delivery of material

- by the feeder whereby the speed of the delivery conveyer is varied so that it will automatically operate at such speed that it is substantially fully loaded, and automatic means responsive to the amount of material delivered by the feeder conveyer for varying the speed of said delivery conveyer. 65
129. The combination in a conveyer system of a feeder conveyer, a delivery conveyer for delivering material therefrom, means for driving the said conveyer and automatic means responsive to the delivery of material to the feeder whereby the speed of the delivery conveyer is varied so that it will automatically operate fully loaded responsive to the amount of material delivered by the feeder conveyer to said delivery conveyer. 70
130. The combination in a conveyer system of a feeder conveyer, a delivery conveyer for delivering material therefrom, means for driving said conveyer and automatic means responsive to the delivery of material by the feeder whereby the speed of the delivery conveyer is varied so that it will operate automatically with a predetermined proportion of its full load, responsive to the amount of material delivered by the feeder conveyer to the said delivery conveyer. 75
131. The combination in a conveyer system of a series of conveyers, means for driving the conveyers, means responsive to the delivery of material to the system for automatically starting said series in succession beginning with the delivery end of the system and stopping the series in inverse order and connections whereby the speeds of the conveyers are automatically varied so that each conveyer of the series will operate with a full load per foot of conveyer responsive to the amount of material delivered to the system. 80
132. The combination in a conveyer system, of a feeder, intermediate and delivery conveyers arranged in series relation, means for driving said conveyers, a controller for automatically starting the said conveyers in succession beginning at the delivery end and for automatically stopping said conveyers in succession beginning at the feeder end, and connections whereby the speeds of the conveyers are automatically varied so that the intermediate conveyer will operate with a full load per foot of conveyer responsive to the amount of material delivered by the feeder conveyer and the delivery conveyer will operate with a full load per foot of conveyer responsive to the amount of material delivered to the delivery conveyer by the intermediate conveyer. 85
133. The combination in a conveyer system for mixing material, of a plurality of feeder conveyers, a plurality of delivery conveyers arranged in series relation, man- 90
- ual means for controlling the feeder conveyers for automatically delivering a predetermined amount from selected conveyers, automatic connections between the feeder conveyers and the delivery conveyer whereby in starting the material delivered by the first feeder in the series reaches the second feeder before said second feeder begins to deliver and the material from the first and second feeder reaches a third feeder before the third feeder begins to deliver, and in stopping the delivery of material the feeders stop in inverse order so that substantially all the material delivered by the conveyer system is similarly mixed. 95
134. The combination in a conveyer system for mixing material, of a plurality of feeder conveyers, of a plurality of delivery conveyers arranged in series relation, manual means for controlling the feeder conveyers for automatically delivering a predetermined amount from selected conveyers, automatic connections between the feeder conveyers and the delivery conveyer whereby in starting the material delivered by the first feeder in the series reaches the second feeder before said second feeder begins to deliver and the material from the first and second feeder reaches a third feeder before the third feeder begins to deliver, and automatic means for maintaining a substantially constant delivery from said feeders and in stopping the delivery of material the feeders stop in inverse order so that substantially all the material delivered by the conveyer system is of a predetermined mixture. 100
135. The combination in a conveyer system for delivering material at predetermined intervals for assembling materials, a plurality of feeder conveyers and a plurality of delivery conveyers arranged in series relation, a manual control for selecting the feeder conveyers to be operated, automatic means whereby the first conveyer may deliver a predetermined amount of material and at a predetermined interval of time after such material has passed the second feeder the said second feeder will deliver a predetermined amount of material and at a predetermined interval of time after the material delivered by the second feeder has passed the third feeder the third feeder will deliver a predetermined amount of material, and automatic means whereby the said predetermined intervals will be maintained, and means responsive to the cessation of delivery of material by any of the feeder conveyers for stopping the feeders in inverse order so that substantially all the material delivered by the system is delivered in proper order. 105
- In testimony whereof I have hereunto subscribed my name.
- FRANCIS LEE STUART. 125
